R. R. DOLLINS

AIR CLEANER

Filed May 20, 1926

Inventor
R. R. Dollins

By Clarence O'Brien

Attorney

UNITED STATES PATENT OFFICE.

ROBERT R. DOLLINS, OF MARLAND, OKLAHOMA.

AIR CLEANER.

Application filed May 20, 1926. Serial No. 110,475.

This invention relates to an improved automotive appliance which may be conveniently termed an air cleaner, the same having more particular reference to a device of this 5 class which may be associated either with the carburetor or the crank case.

The principal object is to provide a device for separating finer dust particles from the air before it enters the mouth of the intake 10 of the carburetor, or the breather pipe of the crank case as the case may be.

Briefly, the invention comprises a tank of cylindrical form which is provided with a suitable drain at its bottom, and which is 15 open at its top, together with a unit which is insertible through the open top to simultaneously provide an efficient closure and to bring into play the novel separating means.

The structural features and advantages of 20 the invention derived from the improved construction, will become plainly evident from the reading of the following description in association with the drawings.

In the accompanying drawings forming 25 a part of this application, and in which like numerals are employed to designate like parts throughout the same:—

Figure 1 is a central vertical section thru 30 an air cleaning device constructed in accordance with the present invention.

Fig. 2 is a horizontal section taken approximately upon the plane of the line 2—2 of Fig. 1, looking upwardly.

Fig. 3 is a section in detail taken on the 35 line 3—3 of Fig. 1, looking downwardly.

Referring now to the drawings in detail, it will be seen that the reference character 1 designates generally the tank which, as before stated, is provided at its bottom with an 40 appropriate drain closed by a removable screw plug 3. This tank is adapted to contain a predetermined quantity of liquid which in the present instance, is oil, as indicated at 4. The insertible unit is designated 45 generally by the reference character 5 and this, as is shown, comprises a closing plate 6 having an inturned flange 7 which telescopes snugly into the upper portion.

It will be noticed also, that it has a marginal flange extending outwardly beyond the flange 7, and overlying the upper edge of the

tank. Carried by this cover plate is an intake tube 8 which extends downwardly into the interior of the tank and into close proximity to the normal level of the oil 4. In 55 addition, the cover plate carries an integral cylindrical outlet 9 which, also depends into the interior of the tank and is provided with supporting arms 10 connected to a conical deflector 11.

Forming a part of this insertible unit are upper and lower screens 12 and 13 respectively, which are connected with bracing and supporting rings 14 and 15 respectively. In order to secure rigidity of construction, the rings 14 65 and 15 are connected together by vertical pieces 16 and 17. This forms a frame which is carried by the cover plate with the ring appropriately bracing and supporting the screen. While this adds slightly to the cost 70 of manufacture of the device, it nevertheless makes a reliable insert which can be forced down into the tank through the open top and withdrawn without distorting the screen.

In practice, it is obvious that the air to be 75 cleansed passes downwardly through the tube 8, and the screen 13, in contact with the surface of the coil 4, upwardly through the screen 13, and the superposed screen 12. Owing to the suction produced through the 80 outlet 9, it is sucked upwardly through this. The fluid passing through the outlet, however, encounters the baffle cone 11 which tends to relieve the air of excess oil which it may have picked up.

It is believed that by carefully considering the description of the details and the operation, persons familiar with devices of this class will obtain a clear understanding of the invention. For this reason, a more 90 lengthy description is deemed unnecessary.

While the preferred embodiment of the invention has been specifically described and claimed, it is to be understood that minor changes coming within the field of invention 95 as set forth in the annexed claim may be resorted to if desired.

Having thus described my invention, what I claim as new is:—

As a new product of manufacture, an open 100 top cylinder adapted to contain a predetermined quantity of cleaning liquid, and an in-

sertable unit comprising a cover plate for said supporting structure, one above the said cylinder, an air intake and conducting tube depending from said cover plate, an outlet in said cover plate, a deflector cone carried by the outlet in spaced relation, a skeleton supporting structure depending from the cover plate, and screens carried by

In testimony whereof I affix my signature.
ROBERT R. DOLLINS.
